(57) **CLAIM**

The ornamental design for a cleaning kit for electronic devices, as shown and described.

DESCRIPTION

FIG. 1 is a perspective view of a cleaning kit for electronic devices showing my new design;

FIG. 2 is an exploded view of a cleaning kit for electronic devices in a state of use;

FIG. 3 is another exploded view thereof;

FIG. 4 is a front view thereof;

FIG. 5 is a back view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings depict portions of the cleaning kit for electronic devices that form no part of the claimed design.

1 Claim, 9 Drawing Sheets
